KNITTING MACHINE

Vincent Lombardi, Garden City, N. Y., assignor
to Lombardi Knitting Machine Co., Inc., New
York, N. Y., a corporation of New York

Application April 28, 1936, Serial No. 76,754

31 Claims. (Cl. 66—50)

5

This invention relates to knitting machines and to knitting elements adapted for use therein.

An object of the invention is to provide a simple and effective machine for the production of 5 patterned knitted fabrics of a wide variety of types.

Another object of the invention is the provision in a knitting machine of means for the selective positioning of needles or other knitting 10 elements, which means is of such character that the knitting elements may be readily and effectively manipulated to produce fabrics embodying desirable types of pattern effects and that the possibility of breakage of any of the parts 15 is minimized.

A further object is the provision of a knitting element particularly adapted for a highly desirable type of selective positioning.

Other objects of the invention will in part be 20 obvious and will in part appear hereinafter.

The invention accordingly comprises the features of construction, combinations of elements, and arrangement of parts, which will be exemplified in the constructions hereinafter set forth and 25 the scope of the application of which will be indicated in the claims.

For a fuller understanding of the nature and objects of the invention, reference should be had to the following detailed description taken in 30 connection with the accompanying drawings, in which:

Figure 1 is a view taken in vertical section thru a portion of a machine embodying the invention;

Fig. 2 is a similar view taken thru a different needle slot, and showing the parts in a different position;

Fig. 3 is a view similar to Fig. 1, showing the parts in still another position;

Fig. 4 is a somewhat diagrammatic side view showing the operating parts and illustrating the needle positioning;

Fig. 4a is a detail view similar to Fig. 1 showing a modified form of construction;

Fig. 5 is a view similar to Fig. 1, illustrating a modified form of machine embodying the invention;

Figs. 6, 7, and 8 are similar views showing the parts in different positions;

Figs. 9, 10, and 11 are enlarged fragmentary transverse sectional views thru the pattern wheel of Figs. 5-8;

Fig. 12 is a view similar to Fig. 4 illustrating the operation of the machine of Figs. 5-11;

Fig. 13 is a view similar to Fig. 1, illustrating another modification;

Figs. 14 and 15 are views similar to Figs. 1 and 4 respectively, illustrating still another type of machine embodying the invention;

10

Fig. 16 is a view similar to Fig. 1 illustrating another modification;

Fig. 17 is a similar view illustrating another form of machine embodying the invention;

Fig. 18 is a fragmentary perspective view illustrating the cam of Fig. 17;

Fig. 19 is a fragmentary vertical sectional view illustrating a further modification;

Figs. 20, 21, 22, and 23 are views taken in vertical section thru a portion of another form of 20 machine embodying the invention and showing the parts in different positions; and

Fig. 24 is a sectional view along the line 24—24 of Fig. 22.

In the production of design fabrics, knitting 20 machines utilizing selective mechanism including an inclined pattern wheel is commonly employed. The ordinary pattern wheel, however, is effective to impart only a relatively small movement to the needles, and for this reason separating cams are commonly utilized to impart additional movement to some or all of the selected needles. In spite of various precautions that have been utilized, considerable difficulty has been experienced due to the tendency of 30 needles becoming misplaced from time to time and jamming against the separating cams, with the necessity of stopping a machine while the damage is repaired. Proposals have been made for the provision of pattern wheels having a degree of inclination sufficient to impart larger movements to the needles, but these have not attained a wide range of utility.

With the foregoing and other difficulties in view, the present invention contemplates the provision of knitting machines, and, in certain of its aspects, of knitting elements therefor, of such character that separating movements occurring after a selective positioning of the knitting elements will be positive and certain in operation.

In accordance with the invention there may be provided knitting-element-means at least a portion of which is adapted for longitudinal movement in response to the action thereon by selective means such as a pattern wheel, and at least a portion of which is adapted to be moved laterally during such selective action. The knitting element means may consist of a single knitting element such for instance as a needle, or

35

40

45

50

55

a plurality of cooperating elements, as will be hereinafter exemplified. The lateral movement of the laterally movable portion of the knitting element may be caused by a camming action between the knitting element and a portion of the needle bed in response to longitudinal movement of the knitting element; by a camming action between the knitting element and associated part in response to longitudinal movement of the part; by a resilient action of the knitting element portion in response to longitudinal movement of the portion, or by other suitable arrangement whereby a portion moves laterally in response to longitudinal movement imparted to another portion. A cam or other actuating element acts on those of the laterally movable portions which are suitably positioned laterally, to impart the desired operative movement thereto and passes those laterally movable portions which are otherwise positioned. Such means may be operative merely to either pass or actuate the portions to a given extent. When desired, however, there may be provided in accordance with the invention an arrangement wherein the laterally movable portion is movable between a multiplicity of lateral positions, a plurality of which are such that the portion may be actuated differently, depending upon which of said plurality of positions the portion is in.

30 In accordance with the invention also means may be provided whereby dial needles and similar knitting elements may be selectively actuated with particular definiteness.

While fabrics in which the yarn is laid in, 35 welt stitch fabrics, plural-yarn "interlock" fabrics, such as shown in my Patents Nos. 1,541,230, 1,728,293, 1,728,294, etc., and other design fabrics have been made on different machines; the making of such fabrics successively on a single machine has commonly necessitated the replacement of parts. Inasmuch as it is often desirable to include such types of knitting in a single fabric, or to knit fabrics embodying such types of knitting in rapid succession, the invention also 40 contemplates the provision of mechanism whereby the foregoing and other types of fabrics may be produced in succession without stopping the machine or replacing any of its parts.

While the invention finds its more ready adaptation in circular knitting machines having a stationary needle cylinder, it is to be understood that it is adapted for use in machines wherein the needle bed is of any of a variety of types and is either stationary or movable. While the 45 knitting elements particularly exemplified are latch needles, it is to be understood that the invention is adapted for use in connection with the operation of a variety of types of knitting elements including beard needles, jacks, sinkers, etc. Again while the invention finds its most ready adaptation in machines arranged for the operation of all the needles (or other knitting elements) in accordance with the invention; it is to be understood that, without departing from the scope of the invention in its broader aspects, 50 needles (or other knitting elements) operated in other well known or desired ways may be provided in certain parts of a machine embodying the invention and may be interspersed with needles (or other knitting elements) operated in accordance with the invention; and it is to be particularly understood that the terms "series of 55 knitting-element-means", "series of knitting elements", "series of needles", "series of sinkers", and the like, as used in the appended claims

comprehend a series of members—such for example as needles—with which other members—such for example as needles—are interspersed, as well as a series the members of which are juxtaposed.

5 In the form of construction particularly exemplified in Figs. 1 thru 4, there is provided a needle bed in the form of a stationary needle cylinder 5 which may be of the conventional type, and means comprising supports 6 and 7 10 which are rotatable about the same. The cylinder 5 is formed with a series of slots 8 in which there are provided knitting-element-means consisting in the present instance of knitting elements 9 in the form of needles which, as exemplified, are of the usual latch type, although other types of needles such as beard needles may be provided if desired. Each needle is provided with a butt portion 10. Certain of these butt portions, in the present instance, are of the shape indicated at 11 and include an extension 12 providing long butts for the needles, and others of which, as indicated at 13, are without these extensions and provide a short butt for the needles. The long-butts and the short-butts 15 needles are interspersed about the cylinder. They may be arranged in alternation or in groups of one, two, three, etc. Long-butts or short-butts needles may, indeed, be interspersed in any of a variety of manners,—one form of 20 arrangement being indicated in Fig. 4.

25 A suitable number of yarn feeds 14 are arranged to rotate about the cylinder with the supports 6 and 7. Following each yarn feed there are provided actuator means for the needles. 30 Such means, in the present instance, is carried on the support 6, and comprises a stitch cam 15, an inclined pattern wheel 16, actuating means in the form of an advancing cam 17, and a long-butts actuating cam 18. The pattern wheel is 35 arranged to operate upon the lower surface 19 of the butt portions 10 of the needles and to either pass a needle or to move it longitudinally from a position A to a position B in the usual manner, and thus serves as selecting means for 40 the needles. The cam 11 serves to act on portions 20, hereinafter to be described, of the selected needles to advance certain of the needles from the position B to a tucking position C. The cam 17 carries an adjustable member 21 which, 45 when in the upper position shown in full lines, will cause the selected needles to be advanced fully to a knitting position D. When the cam-portion 21 is in the lower position, indicated by the dot-dash lines, the cam 17 will act only to 50 raise the needles to the tucking position. The cam-portion 21 may be adjusted manually, or the pin 22 may extend outwardly so as to be operated automatically at various periods in the 55 operation of the machine, as by the usual type of pattern chain mechanism. The cam 18 is pivotally mounted and is arranged, when in the full line position shown in Fig. 4, to act on those of the unselected needles which have long-butts and to advance these from the position A to the 60 position C. When in the dot-dash line position, it will not act on the needles. The cam 18 is carried on a rod 24, which may be turned manually to swing the cam, or may be operated automatically as by pattern chain mechanism of the 65 usual type.

70 There is also provided in the present instance a cam 25 similar to the cam 18 but arranged to operate, when in the full line operative position, on the surfaces 19 of all the butt portions. This 75

cam may be swung by a rod 26 between an operative and an inoperative position as indicated by the dotted and full lines respectively so as to place all the needles when desired in the fully advanced position D. The rod 26 may be operated similarly to the rod 24.

As will be apparent, for any single type of selection of the needles of a given yarn feed, as by a pattern wheel with a particular type of cutting, there may be produced a variety of design stitches. The needles selected by the pattern wheel may be moved into tucking position by the cam 17 so that the selected needles will catch the yarn but not knit, and the unselected needles will pass the yarn, as in the formation of a laid-in fabric. The selected needles may be moved into knitting position where they will receive the yarn and knit, and the unselected needles left in a retracted position where they will not receive the yarn, as in the formation of a welt stitch fabric. The selected needles may be moved into knitting position, and those of the unselected needles having long-butts may be moved into tucking position. While those of the unselected needles having short-butts are left in a retracted position, as in the formation of "interlock" fabric of the general character of that described in my below noted patents. All the needles may be advanced to knitting position. Other variations may be obtained. By the provision of a plurality of yarn feeds and suitable cuttings on the pattern wheels which will cause various needles to knit at different yarn feeds, there may be provided a single or double "interlock" fabric, such as exemplified in my Patents Nos. 1,541,230, 1,728,293, 1,728,294, etc. There may also be provided a laid-in fabric wherein at one yarn feed certain of the needles are in retracted position and the remainder of the needles are in tucking position and at a succeeding yarn feed all of the needles are arranged to knit, or a welt stitch fabric wherein at one yarn feed certain of the needles are in fully advanced position and the remaining needles in retracted position and wherein the latter needles are advanced at one or more of successive yarn feeds. The exemplified arrangement is also adapted for the knitting of a wide variety of types of design fabrics, as well as for the knitting of plain Jersey fabric. Moreover, as will be apparent, all these types of knittings may be included in a single piece of goods by a suitable operation of the adjustable cams and without change of the pattern wheels or other selecting means, with the result that patterned fabrics having features impossible without such an arrangement may be readily and effectively secured.

Besides the portions of the needles at 19 which are adapted to be selectively acted upon and selectively moved a short longitudinal distance by the pattern wheel, the needles, in accordance with the present invention, are, as exemplified, formed with portions 27 at their lower ends which are adapted for lateral movement in response to the selective longitudinal movement, the needles being formed at their rear edges with cam surfaces 28 extending under a portion 29 of the cylinder when the needles are in a retracted position and adapted to cause the portion 27 of a needle to be cammed outwardly when this needle is selected and moved longitudinally by the pattern wheel. As will be seen, this outward, —lateral, — movement of the needle accompanies the longitudinal movement thereof by the pattern wheel. The portions 27 of the needles are also formed with a cam-engaging or "butt" surface 26

adapted to be engaged by the cam 17 when a portion 27 is in an outward position, but not when a portion 27 is in an inward position. Accordingly the surfaces 20 of those needles which are advanced by the pattern wheel will be engaged by 5 the cam 17, whereas the lower parts of the needles which are received in the slots of the pattern wheel and not advanced will ride entirely behind the cam 17.

As will be apparent, it is not essential that all 10 of the needles be formed with lower portions of the character exemplified, but some of them may be of any ordinary or suitable form. However, by forming all of the needles as exemplified, a greater 15 flexibility of design is obtained than when ordinary needles are utilized at certain points.

The modification of Fig. 4a is generally similar to Figs. 1-4, except that the knitting element is a needle jack. The parts corresponding to those of Figs. 1-4 are given the same reference 20 characters with primes attached thereto. Thus, 9' is the jack, while each needle 9' has a butt 10' certain interspersed ones of these being long-butts 12' and the others being short-butts 13'. Each jack has a butt 10', the lower surface 19' of 25 which is operated upon by the pattern wheel 16' in the manner of Figs. 1-4. The lower ends of the jacks have portions 27' for lateral movement by means of the cam surface 28' in the manner of the elements of Fig. 1. The cam-engaging 30 faces 20' correspond to 20 of Fig. 1 and when projected in the path of cam 17 impart a motion to the jack and needle in the manner of Figs. 1-4. Spring 31' of conventional form may be used to 35 normally retain the jacks in the slots.

Instead of the laterally movable portion of the knitting element means being movable to only one lateral position in response to the longitudinal movement of a portion of the means, the laterally movable portion may be movable to any of a 40 plurality of lateral positions so that it will be actuated in different ways depending on which of these plurality of positions it is moved to. An arrangement of this character is shown in 45 Figs. 5 thru 12, wherein the parts are generally similar to the parts shown in Figs. 1 thru 4, and are designated by similar reference numerals carrying the subscript a. In this arrangement the needles 9a are all formed with similar butt portions 10a which may be actuated 50 to move the needles longitudinally a plurality of different extents as by means such as exemplified in my co-pending application, Serial No. 18,091, filed April 25, 1935, or by other means which may be of any known or suitable type. In the form 55 exemplified the pattern wheel 16a comprises an upper plate 31 and a lower plate 32 providing teeth 33 with slots therebetween for the reception of the needle butts and of needle-butt actuators. Two types of such actuators are provided. 60 One type, as indicated at 34, projects only slightly from the body of the pattern wheel so that its period of engagement with a butt 10a during the rotation of the pattern wheel will be short. The other type shown at 35 projects further from 65 the body of the pattern wheel so that it will extend further under the butt and will be in contact therewith for a longer period during the rotation of the pattern wheel and will thus advance the needle to a further extent than an 70 actuator 34. Empty slots, actuators 34, and actuators 35 may be interspersed or otherwise arranged about the periphery of the pattern wheel in any desired manner, one arrangement 75 will be apparent from the operation indicated in

Fig. 12. The lower portions 27a are formed in the present instance with a cam surface 28a which, as exemplified, comprises a sloping surface portion 36, a sloping surface portion 37 and an intermediate flat surface portion 38. There is also provided, besides a cam-engaging shoulder 20a, an additional cam-engaging shoulder 20aa spaced from the shoulder 20a. These shoulders are adapted when in an outward position to be engaged by a cam 39 which serves to advance the needles. As will be apparent, when a needle is advanced a short distance from the position E to the position F, as by an actuator 34, the surface 20aa will be in position to be engaged by the cam 39, but the surface 20a will still be at the rear of the cam. Accordingly the cam will advance the needle from the position F to a tucking position H. When, however, the needle is advanced a longer distance from the position E to the position G, as by the actuator 35, then the cam will engage the surface 20a and will move the needle to fully advanced knitting position I. By the provision of the flattened portion 38 of the rear surface 29a, assurance is had that the needle will be accurately positioned for the engagement of the surface 20aa by the cam. It will be appreciated, however, that in certain instances the surface 29a may slope continuously. It will likewise be appreciated that in accordance with the invention in its broader aspects, the needle bed may be formed with a sloping surface at that portion which is contacted by a laterally movable portion of the needles, such as 27 and 27a, it being possible that needle surfaces 29, 36, and 37 for instance, may have a single point contact with a sloping surface on that portion of the needle bed against which they work.

In Fig. 12, needles a, b, c, e, h, and k are shown in retracted position; needle d is shown as engaged by an actuator 34; needle f is shown as engaged by an actuator 35; needle g is shown as moved to the position G by an actuator 35. Needles i and j are shown as moved to the position F by an actuator 34, the cam 39 having contacted the surface 20aa of the needle j; needle l is shown with its surface 20a engaged by the cam 39; needle m is shown in tucking position H after its surface 20aa has cleared the cam 39; and needle n is shown in advanced position I after its surface 20a has cleared the cam. Needles e, h, and k are shown as being or having been passed by the empty slots of the pattern wheel; needles f, g, l, and n as having been engaged by the actuators 35; and needles i, j, and m as having been engaged by the actuators 34.

As will be appreciated, a wide variety of types of selective means may be utilized for selectively imparting longitudinal movement to the needles. One simple form of such means is exemplified in Fig. 13 wherein the construction is generally similar to that of Fig. 5 and wherein similar parts are identified by similar reference numerals except that the subscript b is used. In this case the butts 10b on the needles are selectively actuated by a cam 40 which is movable by means of a handle 41 from a position indicated in dotted lines wherein it will not contact the butts to a position shown in full lines in which it will contact the butts and move the needles sufficiently to laterally project their cam-engaging surfaces 20bb into position to be engaged by a cam 39b, or to a position such as shown in dot-and-dash lines wherein it will advance the needles sufficiently to move a surface 20b into position to be engaged by the cam 39b.

It will furthermore be appreciated that in instances where the provision of a cam which extends between needle-butt positions is not undesirable, there may be provided an arrangement wherein the lateral movement of the knitting element is only of a single extent and wherein additional selective action is obtained by differences in longitudinal movement. In Figs. 14 and 15 there is shown an arrangement similar to that of Figs. 5-12, but of this nature. In these figures similar reference numerals are utilized, but with the subscript c. A pattern wheel 16c similar to the pattern wheel 16a is utilized to advance the needles to either of two different positions. The lower end 27c of the selected needles will be moved laterally by engagement of the needle bed by a single short sloping surface 29c on the needles. When a needle is moved longitudinally only a short distance, a cam-engaging surface 20cc will be engaged by a cam 39c, and the needle advanced to tucking position thereby, but a cam-engaging surface 20c will ride beneath this cam. On the other hand, when a needle is advanced a longer distance by the pattern wheel, the surface 20c will be engaged and the needle advanced to knitting position thereby.

In accordance with the invention in its broader aspects moreover, the portion of the knitting-element-means which is moved longitudinally need not be integral with the portion of the knitting-element-means which is moved laterally, but the knitting-element-means may consist of portions in the form of separate cooperating elements. Constructions of this nature are shown in Fig. 16 and Figs. 20-24. In Fig. 16 there is shown a needle 42 having a butt 43 adapted to be engaged by a stitch cam 15d for the retraction of the needles. The lower parts 27d of these needles are formed with cam-engaging surfaces 20d adapted to be moved between a multiplicity of lateral positions in one of which, as shown by the nearest needle, it will not be engaged by a cam, in another of which it will be engaged by an actuating cam 44, and in still another of which it will be engaged by an actuating cam 45. It will be appreciated in this connection that a knitting element may be formed with a plurality of cam-engaging surfaces adapted to be knitted by a single cam surface, as in Fig. 5, or with a single cam-engaging surface adapted to be engaged by a plurality of cam surfaces as in Fig. 16. It is to be noted that in the present instance the surfaces 20d on the needles, and the cooperating surfaces on the cams 44 and 45 are inclined outwardly so as to assure an effective grip of the cams on the needles. The lower surface 46 of the needles is inclined outwardly and downwardly from the bed, and in order to effect the lateral movement of the portions 27d of the needles there are provided elements 47 each constituting a portion of a knitting-element-means consisting of the needle 42 and the element 47. Each element 47 is formed with a downwardly and outwardly inclined upper surface 48 adapted to bear against the surface 46 on its needle and to thrust the lower portion of the needle outwardly when the element 47 is moved upwardly. The extent of the lateral movement of the portion 27d will depend on the extent of the upward movement of the element 47. The elements 47 are provided with butts 10d adapted to be selectively acted upon by a pattern wheel 16d similar to the pattern wheel 16a; the shorter actuators on the pattern wheel being arranged to advance the elements 47 sufficiently to move the laterally

movable portions 21d to a position to be engaged by the cam 44, and the longer actuator elements on the pattern wheel being arranged to advance the elements 47 sufficiently to move the portions 5 21d into a position to be engaged by the cam 45.

In certain instances dependence on cooperating surfaces on a knitting element and on a portion of its bed is undesirable, and in such instances the invention contemplates the provision 10 of means whereby the laterally movable portion of the knitting element is resiliently mounted. One form of such construction is exemplified in Fig. 17 wherein there is illustrated an arrangement generally similar to the arrangement of 15 Fig. 1 and wherein the parts are indicated by similar reference numerals with the subscript e. The needles 9e in this case carry butts 10e which are similar thruout the series of needles and are selectively acted upon by a pattern wheel 16e 20 similar to the pattern wheel 16. The lower ends 21e of the needles are mounted for lateral movement by the provision of a resilient portion between them and the butts. The resiliency residing in the present instance is a narrowed portion 48 which provides a particularly effective 25 yieldability for the tail of the needle. It will be noted that this tail portion 21e is mounted outwardly from the rear of the slot 8e. The portions 21e of the needles are provided with butts 30 49 on which are formed laterally-extending cam-engaging surfaces 20e and longitudinally-extending cam-engaging surfaces 50, and there is provided a cam 51, shown in detail in Fig. 18, for selectively actuating the needles in accordance 35 with the longitudinal position they are in after the passage of the pattern wheel 16e. When a butt 49 is in a lower position as in the case of the foremost needle in Fig. 17, the surface 50 of the butt will be engaged by the forward surface 40 52 of the cam and will ride to the rear of the cam on convexly curved surfaces 53, as indicated at q, and ride along the back thereof and into a recess 54, as indicated at t. Should needles 9e be raised 45 slightly by some inadvertence the surface 50 may ride along the back face of the cam 51. When, however, a needle has been moved to an upper position, and the tail of the needle has swung outwardly, due to its resiliency, in the manner indicated, as in the case of the rear needle shown 50 in Fig. 17 and the needle shown at r, the butts 49 thereof will ride above the forward portion 52 of the cam 51 and will be engaged by a cam surface 55 which will serve, as indicated at s, to advance 55 the needle. As will be seen, whether the longitudinal movement is of such extent that when it is completed a needle such as at r will be spaced above the cam, or whether the longitudinal movement is just of sufficient extent to permit the butt to swing outwardly, the outward (lateral) movement of the needle will accompany the longitudinal movement rather than being an independent movement at a spaced point. The portions 21e of those needles which are not moved longitudinally by the pattern wheel will 60 ride to the rear of the cam and will then be swung out into the recess 54 again by the tension of the portion 48, but will not be advanced by the actuating surface 55, whereas portions which have been moved longitudinally by the pattern 65 wheel will have their butts actuated and will be advanced—as to tucking position, or, if desired, to knitting position—by the actuating surface 55.

In Fig. 19 there is shown a construction which is similar to the construction shown in Fig. 17, 70 except that the forward portion 52e of the ac-

tuating cam 51e is narrowed and is extended forwardly beneath the pattern wheel, and that the butts 49e on the tails of the needles are provided with oblique upper surfaces 56 so that they may be snapped past the portion 52e during 5 the operation of a pattern wheel. When the needles are in their refracted position, the butts 49e are below the portion 52e and ride under it. When, however, a needle is raised by the pattern wheel, the surface 56 thereof will bear against the bottom of the portion 52e and cam the tail rearwardly to swing it on its point of resiliency sufficiently so that the butt 49e will move upwardly behind the portion 52e in the cam 51e and will clear this portion. Thereupon due to the resiliency, the tail will swing back to a position where the butt again projects outwardly so that it will be engaged by the actuating cam surface 55e of the cam 51e. Desirably the forward edge 10 of the portion 52e has an upwardly protruding forward portion provided with a sloping forward surface 57 to assure against the butts 49e jamming against the forward edge of the cam. This forward edge is preferably disposed at a point 15 well in advance where the pattern wheel acts on 20 the needles.

In the operation of machines wherein dial and cylinder needles cooperate in the production of the fabric and in analogous types of machines, it is often desirable that the dial needles be actuated selectively to produce design conformations, as for instance, in accordance with my co-pending application, Serial No. 752,028, filed November 8, 1934. However, it is desirable to avoid complexity in the operating mechanism for the 30 dial needles and it has been found that by utilizing the sinker movement to control the operation of the dial needles, a high degree of simplicity can be obtained. In accordance with the invention there is provided means to impart longitudinal movement to the sinkers whereby the dial needles (or, if desired, jacks therefor) will be moved laterally and to selectively position the dial needles (or jacks). In the exemplified construction this means includes sinker-moving 35 cams and mutually cooperating cam portions on the sinkers and on the dial needles to move the latter laterally in response to the sinker movement, and includes also a rotary pattern member for the selective positioning of the dial needles. 40 In the form of construction exemplified in Figs. 20 thru 24, there is provided cooperating means 45 on the sinkers and on the dial needles for positioning the dial needles for actuation by a cam; and there is also provided a pattern wheel for 50 selectively controlling the position of the dial needles so that the cam will actuate the needles to one or another of different extents, or not at all, as determined by the pattern wheel. In this 55 form of construction there is provided a needle bed 5g, which in the present instance, is in the form of a stationary dial having formed therein radial slots 8g carrying sinkers 60 and dial needles 9g. There are also provided cylinder needles 61 carried on a cylinder 62, the actuation 60 of these needles being carried out as disclosed in my said co-pending application, Serial No. 752,028, in one of the manners exemplified herein, or in any other well known or suitable manner.

Movable about the dial is a suitable number of 70 yarn feeds, and a support 63 carrying operating cams 64 and 65 for the sinkers, a stitch cam 66, an actuating cam 39g and a flat rotary pattern member 67, in association with one or more of 75

the yarn feeds. The sinkers and needles are provided with cooperating cam surfaces 68 and 69 whereby, upon the retraction of a sinker its needle will be moved to an elevated lateral position. Each needle is provided with a butt 10g and with cam-engaging surfaces 20g and 20gg. The portion of the needle on which the surface 20gg is formed is provided with a flat surface 70 adapted to be engaged by actuators on the rotary pattern member 67. This rotary pattern member is provided with peripheral slots 71. In certain of these slots there are disposed short actuators 72 and in others long actuators 73, others of the slots being left empty. The rotary pattern member 67 is so arranged, that when a needle has been elevated by the sinker movement, the needle will be left in elevated position as shown in Fig. 21 if an empty slot in the rotary pattern wheel is juxtaposed therewith; will be partially lowered if a short actuator 72 is juxtaposed therewith; or will be lowered to the position shown in Fig. 20 when a long actuator is juxtaposed therewith. The needles are formed with the bends 74 in the usual manner to prevent them from dropping against the sinkers of their own weight after the support of the sinker has been removed before the operation of the pattern wheel. In operation, a needle and sinker being in the position shown in Fig. 20, the sinkers are retracted by the cam 64 causing a lateral movement of the needles as shown in Fig. 21, due to the camming action of the surfaces 68 on the surface 69. A cam 74 serves to assure against retraction of the needles. Thereupon the sinkers are advanced by the cam 64 so as to move the surface 68 back from under the surface 69. The rotary pattern member then rolls over the needles and will pass a needle, partially depress it, or fully depress it in the manner indicated above. If it is passed, the surface 20g thereof will be engaged by the cam 39g and the needle will be fully advanced as indicated in Fig. 23. If, however, the needle is partially depressed, the surface 20gg thereon will be engaged by the cam 39g and the needle will be advanced a less distance. If the needle has been fully depressed, the cam 39g will engage neither of the cam-engaging surfaces thereon and the needle will be left in a retracted position. The advanced needles will be retracted by the stitch cam 66 in the usual manner.

It will accordingly be seen that there is provided an exceedingly safe and effective means for the production of design fabrics of a wide variety of types.

Since certain changes may be made in the above construction and different embodiments of the invention could be made without departing from the scope thereof, it is intended that all matter contained in the above construction or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

70 The invention claimed is:

1. A knitting machine comprising at least one yarn-feed, a series of needles, means for selecting the needles in a predetermined manner, and adjustable means adapted, depending on the adjustment thereof, to move the selected needles to

tucking position and to leave the unselected needles in retracted position, to move the selected needles to knitting position and to leave the unselected needles in retracted position, and to move the selected needles to knitting position and to move certain of the unselected needles to tucking position while leaving the remainder of the unselected needles in retracted position, as desired, prior to the reception of yarn from a single yarn-feed. 10

2. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, means to impart such longitudinal movement to at least certain of said first mentioned portions and to selectively position the second mentioned portions, the last mentioned means including means to cause the second mentioned portions to be moved laterally when the first mentioned portions are moved longitudinally and as an accompaniment of such longitudinal movement and means to cause a supplemental and selective lateral positioning of the second mentioned portions, and actuating means adapted to selectively engage said second mentioned portions depending on their positioning. 20

3. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, means to impart such longitudinal movement to at least certain of said first mentioned portions and to selectively position the second mentioned portions in a multiplicity of positions, and actuating means adapted to selectively engage said second mentioned portions depending on their positioning. 30

4. A knitting machine comprising a bed, a series of knitting-element-means on said bed, at least a portion of each of said knitting-element-means being adapted to be selectively moved longitudinally by a selecting means and at least a portion of each of said knitting-element-means being adapted to be positioned laterally in response to the longitudinal movement of the first mentioned portion, selecting means adapted to selectively engage the first mentioned portions to impart longitudinal movement of a plurality of selectively-determined extents to the selected portions, and actuating means adapted to engage the second mentioned portions when in certain of said lateral positions and to selectively impart thereto longitudinal movement of a plurality of extents depending upon the extent of longitudinal movement imparted to the first mentioned portions by the selecting means. 45

5. A knitting machine comprising a bed, a series of knitting-element-means on said bed, at least a portion of each of said knitting-element-means being adapted to be selectively moved longitudinally by a selecting means and at least a portion of each of said knitting-element-means being adapted to be positioned laterally in response to the longitudinal movement of the first mentioned portion, selecting means adapted to selectively engage the first mentioned portions to impart longitudinal movement of a plurality of selective extents to selected portions, said second men- 50

tioned portions being movable laterally to a plurality of extents depending on the extent of movement of the first mentioned portions, and actuating means, said second mentioned portions and 5 said actuating means being so arranged that the actuating means will engage the second mentioned portions and move them longitudinally to one extent when they have been moved laterally to one extent and to move them longitudinally to 10 another extent when they have been moved laterally to another extent.

6. A knitting machine comprising a bed, a series of needles on said bed, at least a portion of each of said needles being adapted to be moved longitudinally by a selecting means and at least a portion of each of said needles being adapted to be disposed in any of a plurality of lateral positions, means for thrusting a second mentioned portion laterally when a first mentioned portion 15 is moved longitudinally, selecting means to selectively engage the first mentioned portions to selectively impart longitudinal movement thereto, and actuating means adapted to engage said second mentioned portions when in certain of 20 said lateral positions.

7. In a knitting machine, a needle bed, a series of needle slots in said bed, knitting elements in at least certain of said slots, means on said knitting elements to cause a portion of each of said knitting elements to be moved laterally as an accompaniment of the longitudinal movement thereof, means to selectively impart longitudinal movement to said knitting elements with accompanying lateral movement, cam means, said cam 30 means and said bed being mounted for relative movement in a direction transverse of said slots, and means on said portions adapted to be engaged by said cam means to impart longitudinal movement to the knitting elements when said 40 portions have been moved laterally.

8. In a knitting machine, a bed, a series of knitting elements on said bed, means on said knitting elements to cause a portion of each of said knitting elements to be moved to a plurality of 45 different positions during the longitudinal movement thereof, means to selectively impart such longitudinal movement to said knitting elements, cam means, and a plurality of shoulders on individual ones of said portions and adapted to be engaged by said cam means to impart longitudinal movement of different extents to the knitting elements when said portions thereof have been moved to said positions respectively.

9. A knitting machine comprising a needle bed, 55 a series of needle slots in said bed, knitting elements in at least certain of said slots, actuator mechanism, said actuator mechanism and said bed being mounted for relative movement in a direction transverse of said slots, means forming a part of said actuator mechanism for selectively advancing the knitting elements as an accompaniment of said relative movement, means to cause lateral movement of a portion of each knitting element when so advanced, each of said 60 portions being formed with a shoulder adapted to be moved into a path of movement of a part of said actuator mechanism by such lateral movement, and means forming a part of said actuator mechanism and adapted to engage at least 65 certain of said shoulders when the portions carrying the same have been moved laterally and to further advance the knitting elements.

10. A knitting machine comprising a bed, a series of knitting elements on said bed, actuator mechanism, said actuator mechanism and said 70

bed being mounted for relative movement, means forming a part of said actuator mechanism for selectively advancing the knitting elements a plurality of extents during said relative movement, means to cause lateral movement to one 5 extent of a portion of each knitting element when advanced to one extent and to cause lateral movement of said portion to another extent when advanced to another extent, each of said portions being formed with a plurality of shoulders 10 adapted to be moved respectively into the path of movement, and cam means forming a part of said actuator mechanism and adapted to engage whatever shoulders are in its path of movement and to actuate said knitting elements to one 15 extent when one of said shoulders is in its path and to actuate said knitting elements to another extent when another of said shoulders is in its path and to pass said knitting elements when neither of said shoulders are in its path. 20

11. A knitting machine comprising a bed, a series of knitting elements on said bed, each of said knitting elements having a resilient tail and each tail being formed with a cam-engaging surface, selecting means for selectively imparting 25 longitudinal movement to the knitting elements, at least one yarn feed, a cam member formed with a cam surface adapted to engage the cam-engaging surfaces of the knitting elements which are selectively movable longitudinally, said cam 30 member being formed with a portion in the path of movement of said tails in preparation for yarn manipulating action at a single yarn feed whereby by said tails may yield resiliently when they meet said portion but will be swung out by their 35 resiliency into cam-engaging position when they have been moved to a given longitudinal extent by said selecting means.

12. A knitting machine comprising a dial bed, a series of knitting-element-means on said bed, 40 each of at least a plurality of said knitting-element-means including a sinker and a needle, and cooperating means on the sinkers and on a portion of the knitting-element-means other than the sinker for effectuating a control of the 45 operation of said needles in response to an operation of said sinkers.

13. A sinker-top knitting machine, comprising a series of cylinder needles, a series of dial needles, a series of cooperating sinkers, means to 50 actuate said sinkers, said sinkers being individual to said dial needles, cooperating means on the sinkers and the dial needles to cause a portion of a dial needle to be moved laterally in response to the movement of a sinker, means including the 55 aforesaid means to cause said portions of the dial needles to be disposed in a multiplicity of lateral positions, means to selectively actuate said dial needles to a plurality of different extents in accordance with the lateral positioning of said portions thereof, and means to actuate said cylinder 60 needles.

14. A knitting machine comprising a bed, a series of knitting-element-means on said bed, each of said knitting-element-means comprising 65 a pair of relatively movable elements, cooperating means on each pair of elements to cause a portion of one of the elements to be moved laterally in response to longitudinal movement of the other of the elements, means for causing longitudinal movement of said other of the elements, selecting means for causing supplemental and selective lateral movement of only certain of said laterally moved portions, and means to selectively actuate said ones of said elements in ac- 70-75

cordance with the lateral positioning of said portions thereof.

15. A knitting element comprising a yarn-manipulating portion adapted to receive yarn adjacent the front edge of the element, and a portion spaced from said yarn-manipulating portion and having a cam-engaging shoulder and having also a cam surface on the rear edge of the element and adapted for engagement with a co-operating part of a knitting machine to cause the second mentioned portion to be moved laterally during relative movement of the knitting element and the cooperating part longitudinally of the knitting element.

16. A needle comprising a yarn-manipulating portion adapted to receive yarn adjacent the front edge of the needle, and a portion spaced from said yarn-manipulating portion and formed to provide a generally lateral surface adapted to be engaged by cam means when suitably disposed and to provide a cam surface on the rear edge of the needle and adapted for engagement with a co-operating part of a knitting machine to cause the second mentioned portion to be moved laterally when the knitting element is moved longitudinally.

17. A knitting element comprising a yarn-manipulating portion adapted to receive yarn adjacent the front edge of the element, and a portion spaced from said yarn-manipulating portion and formed to provide a plurality of longitudinally spaced generally lateral surfaces each adapted to be engaged by cam means when suitably disposed and to provide at least one cam surface on the rear edge of the element and adapted for engagement with a co-operating part of a knitting machine to cause the second mentioned portion to be moved laterally when the knitting element is moved longitudinally.

18. A knitting element comprising a yarn-manipulating portion adapted to receive yarn adjacent the front edge of the element, and a portion spaced from said yarn-manipulating portion and formed to provide at least one generally lateral surface adapted to be engaged by cam means when suitably disposed, and to provide at least one cam surface on the rear edge of the element and adapted for engagement with a co-operating part of a knitting machine to cause the second mentioned portion to be moved laterally different extents when the knitting element is moved different extents longitudinally.

19. A knitting element comprising a yarn-manipulating portion adapted to receive yarn adjacent the front edge of the element, and a portion spaced from said yarn-manipulating portion and formed to provide a plurality of longitudinally spaced generally lateral surfaces each adapted to be engaged by cam means when suitably disposed and to provide a cam surface on the rear edge of the element and adapted for engagement with a co-operating part of a knitting machine to cause the second mentioned portion to be moved laterally to one extent when the knitting element is moved longitudinally a given extent and a cam surface on the rear edge of the element and adapted to engage said part to cause said second mentioned portion to be moved laterally to a further extent when the knitting element is moved longitudinally a further extent.

20. A knitting machine needle formed with a resilient tail, a butt on said tail, one of the oppositely-disposed edges of said butt being inclined substantially from the end of the butt and in the direction in which said tail extends whereby when

said inclined surface meets an obstruction the butt will slide behind the obstruction due to the resiliency of the tail, and the other of said oppositely disposed edges being a cam-engaging surface forming an angle not substantially greater than a right angle with a line extending longitudinally of said tail as the tail extends beyond said edge.

21. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, each of said second-mentioned portions being formed with a butt surface adapted to be engaged by an advancing cam to advance said second-mentioned portions longitudinally and each of said knitting-element-means including a yarn-manipulating element adapted to be advanced when the second-mentioned portion thereof is advanced, selective means to impart longitudinal movement to selected ones of the first-mentioned portions of the knitting-element-means to cause the second-mentioned portions thereof to be moved laterally as an accompaniment of said longitudinal movement, and cam means adapted to engage said butt surface on each of said second-mentioned portions which has been moved laterally to advance the same and to advance therewith the yarn-manipulating elements thereof to a yarn-manipulating position.

22. A knitting machine comprising a bed, a series of knitting-element-means on said bed, a needle forming at least a part of each of said knitting-element-means, at least a portion of each of said knitting-element-means being adapted to be moved longitudinally and at least a portion of each of said knitting-element-means being adapted to be moved laterally as an accompaniment of such longitudinal movement, each of said second portions being formed with a butt surface adapted to be engaged by an advancing cam to advance said second-mentioned portions longitudinally so as to move said needles into yarn-receiving position, an oblique pattern wheel adapted to selectively impart longitudinal movement to the first-mentioned portions of certain of said knitting-element-means to cause the second-mentioned portions thereof to be moved laterally, a yarn feed, and cam means adapted to engage said butt surfaces of each of the second-mentioned portions which has been moved laterally and to advance the same to dispose the needles to receive yarn from said yarn feed.

23. A knitting machine comprising a bed, a series of needles on said bed, a yarn-feed, means to selectively impart longitudinal movement to said needles, means to cause a portion of those needles which are moved longitudinally by the last-mentioned means to move laterally as an accompaniment of said longitudinal movement, and means to engage those portions of the needles which have been moved laterally to advance such needles for reception of yarn from said yarn feed.

24. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, each of said knitting-element-means comprising a yarn-manipulating element adapted

to be advanced when the second-mentioned portion thereof is advanced, said second-mentioned portions comprising resilient tails, means including said resilient tails and the surface of a cam member to cause a lateral movement of said second-mentioned portions as an accompaniment of such longitudinal movement, and means to engage a part of each of said second-mentioned portions which has been moved laterally to advance the same and to advance the associated yarn-manipulating element to a yarn-manipulating position.

25. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, each of said second-mentioned portions being formed with a butt surface adapted to be engaged by an advancing cam to advance said second-mentioned portions longitudinally and each of said knitting-element-means including a yarn-manipulating element adapted to be advanced when the second-mentioned portion thereof is advanced, means to impart such longitudinal movement to at least certain of said first mentioned portions with an accompanying lateral movement of the second-mentioned portions and to selectively position the second-mentioned portions in a plurality of lateral positions, and cam means adapted to engage said butt surface on each of said second-mentioned portions which is in a given one of said lateral positions to advance the same and to advance therewith to a yarn-manipulating position the yarn-manipulating element of the knitting-element-means of which it is a portion.

40. 26. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, each of said second-mentioned portions being formed with a butt surface adapted to be engaged by an advancing cam to advance said second-mentioned portions longitudinally and each of said knitting-element-means including a yarn-manipulating element adapted to be advanced when the second-mentioned portion thereof is advanced, means to impart such longitudinal movement to at least certain of said first-mentioned portions and to selectively position the second-mentioned portions, the last mentioned means including a pattern wheel adapted to act selectively to impart longitudinal movement to the first-mentioned portions and means whereby the second-mentioned portions of the knitting-element-means whose first-mentioned portions have been moved longitudinally will be moved laterally as an accompaniment of said longitudinal movement, and cam means adapted to engage said butt surface on each of said second-mentioned portions which has been moved laterally to advance the same and to advance the associated yarn-manipulating element to a yarn-manipulating position.

70. 27. A knitting machine comprising a bed, a series of knitting-element-means on said bed, at least a portion of each of said knitting-element-means being adapted to be moved longitudinally and at least a portion of each of said knitting-ele-

ment-means being adapted to be moved laterally as an accompaniment of such longitudinal movement, means to impart such longitudinal movement to at least certain of said first-mentioned portions and to selectively position the second-mentioned portions longitudinally, said second-mentioned portions comprising resilient tails, means including said resilient tails to cause a lateral movement of said second-mentioned portions due to such longitudinal movement, and actuating means adapted to selectively engage said second-mentioned portions depending on the positioning.

28. A knitting machine comprising a bed, a series of knitting-element-means on said bed, at least a portion of each of said knitting-element-means being adapted to be moved longitudinally and at least a portion of each of said knitting-element-means being adapted to be moved laterally as an accompaniment of such longitudinal movement, each of said second-mentioned portions being formed with a butt surface adapted to be engaged by an advancing cam to advance said second-mentioned portions longitudinally and each of said knitting-element-means including a yarn-manipulating element adapted to be advanced when the second-mentioned portion thereof is advanced, means to impart such longitudinal movement to at least certain of said first-mentioned portions, cooperating means on the second-mentioned portions and on other parts of the machine to cam said second-mentioned portions laterally during such longitudinal movement, and cam means adapted to engage said butt surface on said second-mentioned portions in accordance with the lateral position of said second-mentioned portions, said machine including a pattern wheel having a selecting action so that certain of said second-mentioned portions will be in position to be engaged by said cam means so as to be advanced with the consequent advance to a yarn-manipulating position of the yarn-manipulating element associated therewith and other of said second-mentioned portions will be in a position to be passed by said cam means.

45. 29. A knitting machine comprising a bed, a yarn-feed, a series of knitting-element-means on said bed, at least a portion of each of said knitting-element-means being adapted to be selectively moved longitudinally by a selecting means and at least a portion of each of said knitting-element-means being adapted to be moved laterally in response to such longitudinal movement of the first-mentioned portion, selecting means adapted to selectively engage the first-mentioned portions to impart said longitudinal movement to the selected portions, means to impart lateral movement to the second-mentioned portions of only those knitting-element-means of which the first-mentioned portions are selected, means forming a part of each of said knitting-element-means for manipulating yarn from said yarn-feed, and means for actuating said knitting-element-means to cause the manipulation of said yarn thereby, the last-mentioned means including means adapted to engage said second-mentioned portions to which lateral movement has been imparted and to advance the same.

70. 30. A knitting machine comprising a bed, a yarn-feed, a series of needles on said bed, means to selectively impart longitudinal movement to said needles, each of said needles having a portion adapted to be disposed in different lateral positions, cam means adapted to engage said portions when in certain of said lateral positions,

and to dispose said needles in position to receive yarn from a yarn-feed, and means for selecting said needles and for causing said portions of only the selected needles to be in given ones of said 5 certain of said lateral positions.

31. A knitting machine comprising a bed, a series of knitting elements on said bed, a portion of each of said knitting elements being laterally movable and having a butt surface, selecting 10 means for selectively imparting longitudinal movement to the knitting elements, means to actuate the knitting elements when said portions are moved longitudinally and are in a given lateral position, said actuating means comprising a

member having a cam surface and having also a forwardly extending surface in advance of said cam surface and continuous therewith and disposed in position to extend under the butt surface of a portion of a knitting element which has 5 been so moved longitudinally and is in said given lateral position, and resilient means tending to swing said portions into said lateral positions when they are moved longitudinally to a position wherein said butt surfaces may be juxtaposed with 10 said forwardly extending surface of said cam member.

VINCENT LOMBARDI.
